CRAVAT HOLDER

Albert W. Lindquist, Cranston, R. I., assignor to
 Freeman-Daughaday Company, a corporation
 of Massachusetts

Application February 26, 1935, Serial No. 8,257

11 Claims. (Cl. 24—49)

This invention relates to a cravat holder; and has for one of its objects the provision of a device for restraining lateral movement of the cravat, although permitting it to be moved vertically relative to the shirt.

Another object of the invention is the provision of means by which the cravat may be easily threaded through the portions which are designed to embrace it.

10 Another object of the invention is the provision of means to cause the portion which extends across the front of the cravat to be capable of movement directly away from the cravat to a limited extent for easy insertion of the cravat 15 between the member which extends across the front of the cravat and the member which engages the shirt beneath the cravat, thereby affording a larger opening through which the cravat may be passed.

20 Another object of the invention is the provision of resilient means for causing the parts to contract when released from manual engagement.

Another object of the invention is to so shape and hingedly mount the member which extends 25 across the front of the cravat that it may be swung about its mounting and without detachment increase the size of the opening between it and the part beneath the cravat for the threading of the cravat into embracing position.

30 With these and other objects in view, the invention consists of certain novel features of construction, as will be more fully described, and particularly pointed out in the appended claims.

In the accompanying drawing:

35 Fig. 1 is a front view of the device in position as worn;

Fig. 2 is a front elevation detached from the cravat;

Fig. 3 is a plan view;

40 Fig. 4 is a back view of the device;

Fig. 5 is a section on line 5—5 of Figure 2 with the front bar removed;

Fig. 6 is a view similar to Figure 5 showing the front bar in expanded position or moved away 45 from the back member;

Fig. 7 is a sectional view on substantially line 7—7 of Figure 6;

Fig. 8 is a front elevation of a modified construction of the device;

50 Fig. 9 is a sectional view showing the mounting of the links between the members as shown in Figure 8.

In the use of cravat holders, it is desirable that the cravat be restrained from lateral movement 55 relative to the shirt, but yet permitted a vertical

movement; and in order to provide such a construction, it is usual to have a portion embracing the cravat through which the cravat must be threaded; and where a rigid or stiff member extends across the front of the cravat, it is sometimes desirable to provide a greater opening between it and the back bar or member which engages the front of the shirt beneath the cravat than when these members are in working position for more easy threading of the cravat between the two; and in order to accomplish this result, I have so connected the front member and the back member that the front member may be resiliently moved directly away from the back member, and when released will move back into its original working position; and I have so shaped the front bar or member and hinged it to the back member that when it is swung about the hinge mounting, it enlarges the opening between the members; and the following is a more detailed description of the present embodiment of this invention, illustrating the preferred means by which these advantageous results may be accomplished:

With reference to the drawing, a member 10, 25 which I may term a back bar, is provided with some sort of a jaw 11 to receive between this jaw 11 and this bar 10 the edge of the shirt of the wearer. Any convenient means being acceptable for mounting this back bar or member on the shirt beneath the cravat.

The back bar is of a hollow or tubular construction, as shown at 13 in Figure 7, and has mounted therein a link 14 which is pivoted by means of the trunnions 15 in recesses 16 in the bar suitably shaped to receive them. This link 14 is hinged to a second link 17 which has an eye 18 for hingedly connecting it to the end of the front bar 20, as illustrated at 21. This link 17 is provided with a finger 22 which slidably engages the front portion of the back bar 10 to guide it in its movements, while a flat leaf spring 23 mounted in this hollow back bar engages the end 24 of the link 14, tending to swing it about its pivot 15 and move its end 25 inwardly, which movement causes the finger 22 to engage and slide along the back bar and swing the end of the front bar 20 towards the back bar into collapsed position. A similar arrangement connects the front and back bars at both ends so that the front bar 20 may be pulled directly bodily away from the back bar 10 to enlarge the distance between these members through which the cravat may be passed.

The front member or bar 20 is of a relatively stiff or rigid material and is of somewhat V shape 55

with legs 26 at its ends. Any suitable shape being acceptable, but preferably a shape which has offset portions so that when the bar is swung about its hinge connection 21 from the position 5 illustrated in Figure 2 to the position illustrated in Figure 6, the opening or space between the members 10 and 20 will be increased and there will be greater space for the threading or passing of the cravat between the members. This opening 10 can also be increased by lengthening the parallel leg portion 26 of the front member 20.

In Figure 8, I have illustrated a helically coiled spring 30 within the tubular back bar and links 31 having trunnions 32 slidably in the slot 33 at 45° 15 to the direction of length of this back bar, their inner ends being suitably attached to the spring 30 through the link 36 to better direct the pull thereon. The outer ends of these links 31 are provided with eyes 34 to be attached to the front 20 member 20 in the same manner as above indicated. The arrangement is such that as the members 10 and 20 are pulled apart, the links will slide in their slots of 45° and at the same time pivot to maintain their hinge eyes 34 at the same 25 distance apart and allow a parallel movement of the members away from each other. It will be understood that there are slots 35 provided in the front of the member 10 to permit this pivotal movement. When the tension is released, the 30 spring will draw the links back into contracted position and the members toward each other.

The foregoing description is directed solely towards the construction illustrated, but I desire it to be understood that I reserve the privilege of 35 resorting to all the mechanical changes to which the device is susceptible, the invention being defined and limited only by the terms of the appended claims.

I claim:

1. A cravat holder comprising a relatively stiff 40 member for extending across the front of the shirt beneath a cravat, a second relatively stiff member for extending across the front of the cravat, and means comprising links pivotally connecting the ends of said members together, and means independent of said second member for securing said first member to a shirt.

2. A cravat holder comprising a relatively stiff 50 member for extending across the front of the shirt beneath a cravat, means secured to said member and acting therewith for securing the same to the shirt, a second relatively stiff member for extending across the front of the cravat, and means comprising links movable with reference to each member for connecting the ends of 55 said members together.

3. A cravat holder comprising a relatively stiff member for extending across the front of the shirt beneath a cravat, means for securing the same to the shirt, a second relatively stiff member 60 for extending across the front of the cravat, and means comprising a pair of links pivoted together connecting the opposite ends of said members together.

4. A cravat holder comprising a relatively stiff 65 member for extending across the front of the shirt beneath a cravat, means secured to one of said members for securing the same to the shirt, a second relatively stiff member for extending across the front of the cravat, and means 70 for securing and resiliently drawing the ends of said members toward each other.

5. A cravat holder comprising a relatively stiff member for extending across the front of the

shirt beneath a cravat, means for securing the same to the shirt and positioned to be located beneath the cravat, a second relatively stiff member for extending across the front of the cravat, means connecting the ends of said members together, and means for causing said connecting means to move and draw the members toward each other. 5

6. A cravat holder comprising a relatively stiff member for extending across the front of the shirt 10 beneath a cravat, means for securing the same to the shirt, a second relatively stiff member for extending across the front of the cravat, means comprising a pair of links pivotally connecting the ends of said members together, and 15 resilient means acting on one of the links of each pair tending to move it in one direction.

7. A cravat holder comprising a relatively stiff member for extending across the front of the shirt beneath a cravat, means for securing the same to the shirt, a second relatively stiff member for extending across the front of the cravat, means comprising a pair of links pivoted together and connecting the ends of said members, and 20 resilient means acting on one of the links of each pair tending to move it in a direction to cause 25 said members to move toward each other.

8. A cravat holder comprising members for extending across the front of the shirt beneath a cravat, means for securing the same to the shirt, 30 a second member for extending across the front of the cravat, means comprising links connecting the ends of said members together, said means comprising at one end a link pivoted on the first 35 said member, and a second link hinged to the first link and second member, and resilient means for moving said first link to swing the connection to the second link inwardly.

9. A cravat holder comprising members for extending across the front of the shirt beneath a 40 cravat, means for securing the same to the shirt, a second member for extending across the front of the cravat, means comprising links connecting the ends of said members together, said means comprising at one end a link pivoted on the first 45 said member, and a second link hinged to the first link and second member, and resilient means for moving said first link to swing the connection to the second link inwardly, said second link having a projecting finger engaging said first 50 member for guiding the movement of the second link upon movement of the first said link.

10. A cravat holder comprising a relatively stiff member for extending across the front of the shirt beneath a cravat, means for securing the same to the shirt, a second relatively stiff member for extending across the front of the cravat, and means comprising a pair of links pivoted together and connecting the ends of said members, said pairs of links being foldable one 60 on the other to move said members into contiguous relation.

11. A cravat holder comprising a relatively stiff member for extending across the front of the shirt beneath a cravat, means for securing the same to the shirt, a second relatively stiff member for extending across the front of the cravat, means comprising a pair of links pivoted together and connecting the ends of said members, said pairs of links being foldable one on the other, and resilient means to move said links into foldable relation to thereby move said members into contiguous relation. 65

ALBERT W. LINDQUIST. 70
